TRANSFER TAIL WINDER FOR CONING MACHINES

Leroy S. Converse, Ridley Park, and Edgar S. Kennedy, Norristown, Pa., assignors to The Viscose Company, Marcus Hook, Pa., a corporation of Pennsylvania.

Application September 30, 1935. Serial No. 42,970

6 Claims. (Cl. 242—43)

This invention relates to a transfer tail winder for coning and similar machines and has for its main object to provide a substantially automatic device for winding a transfer tail at the base of a cone or the like, in an improved and more satisfactory manner than has been heretofore accomplished by manual operations.

It is customary in warping or knitting from cone packages of rayon yarn to tie the end of one cone package to the beginning of another package so as to avoid stopping of cone creels or knitting machines when the first package runs off. In order that the end of one package can be tied to the beginning of a second package it is the general practice in winding such cone packages for the coning operator to wind by hand several turns of yarn around the cone-center near its base and below the main wind or traverse of yarn, before placing the cone-center on the spindle to wind.

Then several turns can be unwound when the cone is used and thus give length enough of yarn to tie to the beginning of a second cone. These several turns of yarn are called the transfer tail.

This invention consists of a suitable guide so placed that when the traverse frame back is in the open position away from the spindle, the thread passes from the supply through the regular traverse guide and then behind or in back of the transfer tail guide. This positioning of the thread is accomplished when the operator after threading through the regular guide, wraps the yarn around the bare metal spindle or cone holder and when the cone-center is then forced over the spindle it carries the thread along its lower edge to the back or wide diameter end of the spindle. This carries it beyond or behind the transfer tail guide so that when the power is applied to the spindle and the spindle rotates in normal clockwise direction all of the yarn is wound at the base of the cone until the traverse frame back is raised or closed to the regular starting position. The interval of time during which the operator permits the spindle to rotate with the traverse frame in the open position is determined by the length of transfer tail desired. The average length of tail, however, is obtained by permitting the traverse guide to make from four to six complete traverses, which of course will give from nine to twelve coils or wraps of yarn at the transfer tail.

When the traverse frame back is closed, the arc through which it travels raises the standard thread guide and therefore the thread itself above the level of the transfer tail guide, permitting the 55 yarn to unhook from the transfer tail guide and

assume its regular traverse position further forward on the cone center, without stopping the spindle.

In forming the transfer tail, if the guide holds the yarn in one fixed position the transfer tail is invariably underwound or overwound, or in other words there is no control of the wind, so that the creeling operator or knitter will have difficulty in unwinding the transfer tail without snarling or catching. In addition, should the tail be left on the cone, such an underwound or overwound condition would prevent proper transferring from one cone to another as it would cause excessive thread breakage at this point. This difficulty has been solved in the present device in that the transfer tail guide actually winds the thread onto the base of the cone with a miniature traverse motion, which motion is imparted to the thread by the angle of inclination which the guide makes to the direct vertical. The variable increase and decrease of thread angle from the main or regular traverse guide to the transfer tail guide imparts a reciprocating motion to the thread with the result that the actual horizontal traverse motion of the regular guide is reduced down to give this miniature traverse motion to the thread as it is wound onto the transfer tail.

In the accompanying drawing—

Figure 1 is a side elevation, slightly broken and shown in section, of a cone winding machine showing the present invention as applied thereto, in operation;

Figure 2 is an end elevation of the structure shown in Figure 1, parts being broken away and shown in section;

Figure 3 is a detail showing parts of Figure 2 in another position;

Figure 4 is a plan of the guide according to the present invention; and

Figure 5 is a side elevation of the same.

The portions of the conventional winding machine shown in Figs. 1, 2 and 3 comprise a spindle 10 adapted to receive a cone-center 11 such as a cone or other core for a yarn package 12. The traverse frame back comprises a weighted lever 13 which is pivoted below the spindle, and has a groove in its upper end receiving a traverse bar 14, which is reciprocated by a cam arrangement (not shown). A supporting arm 17 is secured to the traverse bar, and has an upper end on which is mounted a yarn guide 20, to which the yarn passes over a bail 21.

According to the present invention this machine is provided with the transfer tail guide 22.

shown in Figs. 4 and 5. This guide preferably comprises a length of wire having an eye 23 formed in one end, and an upstanding finger 24 at the other end. This guide is mounted as shown in Figure 1, on a stationary part of the winding machine, as by means of a screw 25 passing through the eye 23.

The body of the guide 22 extends substantially horizontally under the cone 11, but is preferably inclined in two directions, slightly upward and slightly away from its stationary mounting. The finger 24 is substantially vertical in a plane parallel to the axis of rotation of the cone, but is inclined toward the other end of the cone.

15 In operation, after threading through the guide 20, when the arm 13 is in the open position away from the spindle as shown in Figures 1 and 2, the free end of the yarn is wrapped around the spindle or cone holder 10 as shown at 30. The cone center 11 is then forced over the spindle, and carries the thread along its lower edge to the back or wide diameter end of the spindle, as at 32.

This position is beyond the finger 24, so that 25 as shown in Figures 1 and 2, the yarn from the guide 20 passes over the transfer tail guide 22, and is retained by the finger 24.

Power is now applied to the spindle 10, while 30 the transfer frame back carried by the arm 13 is still in open position, and all of the yarn is wound at the base of the cone. However, even in the open position of the arm 13, the guide has its usual traverse motion. The variations in tension produced by this traverse motion while the yarn 35 is retained by the finger 24 cause the yarn to ride up and down the inclined surface of the finger 24 a slight amount, which produces a miniature traverse motion sufficient to lay the transfer tail in regular convolutions.

40 When the winding of the transfer tail has been completed, the operator merely releases the arm 13, which swings to its normal winding position shown in Fig. 3. It will be obvious from an inspection of this view that this motion of the guide 45 20 pulls the yarn free of the finger 24, because the guide 20 rides on the surface of the cone-center while the finger 24 is spaced therefrom. Of course the regular winding builds up the thickness of the package and the guide 20 riding there- 50 on moves outwardly therewith, but the finger 24 being located to direct the transfer tail onto the base of the cone below the package, is laterally spaced to clear the package as it increases in diameter.

55 From the foregoing description it will be readily apparent that the present invention has the following advantages over the former manual procedure in winding a transfer tail:

1. Saving of time and labor.
- 60 2. Complete elimination of the running or displacing of twist in the yarn due to the unavoidable passing of the thread between thumb and finger of operator.
3. Elimination of staining of yarn from oil on the operators' fingers.

4. The first layer or traverse of yarn on the regular cone traverse after the tail is wound by the manual method must be laid on in whole or part of a traverse manually by the operator. Any irregularity of the lay of this thread by hand can cause a half-hitch at the critical part of the transfer to cause failure of the same. This device permits the lay of this first traverse with the 75 same precision and regularity as the balance of

the cone is wound thus eliminating any possibility of half-hitches or underwinds.

5 Furthermore any opening of twist at this first layer of yarn on the full width traverse by the passage of the thread between operator's thumb and finger will cause the last layer of 10 yarn to cling to the "fuzz" or "velvet finish" of the paper cone center itself. As the thread is put under tension during transferring such open twist will close up so that the fuzz or nap on the 15 surface of the paper center is gripped between the filaments of the yarn. Faulty transfers owing to the yarn breaking from these causes are eliminated by winding this critical layer or traverse of yarn by this mechanical means.

6. Frequent transferring difficulties are caused by winding the tail manually too high or too low at the base of the cone center. When wound too high the transfer tail is buried by the actual cone 20 traverse of yarn so that several ends or false tails are produced when the creeling operator attempts to use the transfer tail so wound. When wound too low on the cone center the tail is pinched and damaged by the perforations in the trays of the 25 shipping cases and when the double use of the tail described hereafter is employed the residual tail is damaged or pinched by the pads or standards on the cone creel. The use of this device eliminates the foregoing difficulties, in that each 30 tail is wound at a definite fixed and proper position at the base of the cone center.

7. Shiners have been caused by the yarn at transfer tail and first layer on traverse being strained or stretched by the operator when starting a spindle. This device permits winding this 35 portion of the thread with a minimum of yarn tension.

8. As the end of each transfer tail wound by this device is completely covered over or buried by the miniature traverse wind of the tail it 40 permits an easy drawing off of as many coils of yarn required for tying to the second cone. This will leave a residual tail on the cone which may be again used should it be necessary to remove one set or type of yarn from the creel in 45 order to put on another type or denier. At present when this is done in the customer's mill the remnant cones must be run off subsequently without transfer tails as these are broken off during the first set up.

9. With the end of the tail so buried and locked into position permits the tying of the outside end of the cone direct to the inside or tail and to facilitate finding of the transfer tail by the creeling 55 operator as well as eliminating the use of one gummed label which is used at present to fasten the transfer tail to the inside of the cone-center. This method also eliminates the notching of the base of the cone with scissors to prevent chafing of the yarn which passes around the lower edge of the cone-center and so increases the life of reused cone-centers.

What we claim is:—

1. In a yarn package winding apparatus, means 65 for rotating a core, a yarn guide, means for reciprocating said yarn guide along said core, said guide being movable toward said core, in combination with means adapted to intercept yarn between said guide and core for winding a transfer tail, said means being released by approach of said yarn guide toward said core.

2. In a yarn package winding apparatus, means for rotating a core, a yarn guide, means for reciprocating said yarn guide along said core, said 75

guide and reciprocating means being movable away from said core, in combination with means adapted to intercept yarn between said guide and core when said guide and reciprocating means are in their position away from said core, for winding a transfer tail.

3. In a yarn package winding apparatus, means for rotating a core, a yarn guide, means for reciprocating said yarn guide along said core, said 10 guide being movable toward said core, in combination with a stationary transfer tail guide adjacent the driven end of the core adapted to intercept yarn between said guide and core for winding a transfer tail, said yarn being withdrawn from said stationary transfer tail guide by 15 approach of said yarn guide toward said core to normal winding position.

4. In a cone winding machine, means for rotating a cone, means for reciprocating a yarn guide 20 in contact with the cone or yarn thereon, means for mounting said reciprocating means on a pivotal axis parallel to the axis of rotation, and means adjacent the larger end of the cone for intercepting the yarn between the guide and cone and causing the same to wind a transfer tail, said means being released by approach of said 25 yarn guide toward said core.

5. In a cone winding machine, means for rotating a cone, means for reciprocating a yarn guide 30 in contact with the cone or yarn thereon, means for mounting said reciprocating means on a pivotal axis parallel to the axis of rotation, and a

stationary member adjacent the larger end of the cone having an upstanding finger inclined in the direction of traverse for intercepting the yarn between the guide and cone and giving said yarn a miniature traverse for causing the same to wind a transfer tail, when the yarn guide is swung on said pivotal axis away from said cone, approach of said yarn guide toward said cone serving to pull the yarn free of said finger for normal winding. 5

6. In a yarn package winding apparatus, means for rotating a core to wind yarn thereon, a yarn guide, means for reciprocating said yarn guide parallel to the axis of rotation, means for mounting said yarn guide on a pivot parallel to the axis 15 of rotation, whereby said yarn guide is adapted to engage the surface of the core or the yarn already wound thereon, but is movable about said pivot away from said core, in combination with means adjacent the starting end of said core for intercepting the yarn between the core and the yarn guide in its position away from said core to prevent the yarn on the core from following the 20 traverse of the guide, and to cause the yarn being wound on the core to wind a transfer tail at the 25 starting end thereof, said intercepting means being spaced from the core whereby the return of the guide into contact with the core releases the 30 yarn from said intercepting means.
